UNITED STATES PATENT OFFICE.

JOSEPH A. SILVER, OF NEW YORK, N. Y.

RAILROAD SLEEPER AND RAIL FASTENING.

Application filed May 10, 1927. Serial No. 190,321.

This invention is an improved railway sleeper and tie especially designed for use on steam railroads to take the place of the ordinary wooden ties.

5 The principal object of the invention is to provide a metallic sleeper that is to be disposed lengthwise of the rail and is so formed underneath that any ballast that gets under the lip of the sleeper will tend to work itself 10 toward the center of the sleeper and keep the sleeper properly tamped up, the metallic sleepers having numerous perforations therein in order to see that the same are properly tamped up.

15 Another object is to make a metal sleeper which can be economically manufactured so as to make it comparable with the cost of ordinary wooden sleepers.

Another object is to make metallic sleepers 20 that will be durable and reliable while sufficiently light to be easily transportable.

Still another object is to provide novel means for fastening the rails to the sleepers so that they will be firmly secured thereto, 25 and which will enable the rails to be insulated from the sleepers, as required in electric railway signaling systems.

In the accompanying drawings I have illustrated a sleeper and rail fastener embodying the invention, and will describe the same in detail with reference thereto; and summarize in the claims the novel features of construction and novel combinations 30 of parts for which protection is desired.

35 In said drawings:

Fig. 1 is a top plan view of the complete 40 sleeper;

Fig. 2 is a side view thereof;

Fig. 3 is a longitudinal section on the line 45 3—3 of Fig. 1;

Fig. 4 is an enlarged transverse section on the line 4—4, Fig. 1, showing the rail fastening devices;

45 Figs. 5 and 6 are enlarged transverse sections on the lines 5—5 and 6—6 respectively, of Fig. 1;

Figs. 7 and 8 are detail views of one of the 50 adjustable rail clamps.

The sleeper comprises an approximately 55 rectangular or oval casting 1 which is convex on its upper surface and concave on its under surface, and somewhat irregular in cross section, the general contour thereof being illustrated in Figs. 2 to 6 of the drawings. This 60 sleeper has a central longitudinal elongated

portion 1 the top of which is approximately horizontal; at the sides of this central portion the sleeper is curved downwardly as at 1^a, Fig. 5, and beyond these portions 1^a the sides extend outwardly and downwardly on a slight inclination, forming what I term 65 side portions or wings 1^b.

The sleeper is strengthened by integral 70 ribs. As shown it has transversely disposed ribs 1^c on its upper side integral with the 75 wings 1^b and portions 1^a. Intermediate the ribs 1^c are pairs of transverse ribs 1^d and 1^e. The sleeper is further strengthened by transversely disposed ribs 1^f on its underside. The sleeper is also strengthened by integral 80 reinforcing ribs 1^g on its underside, see Fig. 70, which intersect the ribs 1^f as indicated in the drawings.

For the purpose of lightness the shell of 75 the sleeper is preferably provided with numerous openings as at 1^h, which also enable the workmen to see that the sleeper is properly tamped up.

On the top of the longitudinal central portion of the sleeper are formed four seats A, 80 B, C, D, extending in a line from end to end thereof, which seats are adapted to receive blocks W of wood, fiber, or other sound deadening material which blocks are interposed between the seats and the rail R. These 85 blocks may be cut to fit the seats and may be of any suitable thickness, and they are positioned on the seats by projecting lugs 1ⁱ at the edge of the seats, which may be of any desired number and may be cast integral with the sleeper. These lugs projecting 90 from the top side of the plate as shown, prevent lateral displacement of the blocks W when in place on the seats. Transversely disposed ribs 1^j may be arranged between 95 adjacent seats, as indicated in the drawings. For convenience in manufacture these ribs 1^j may be the mouths of the gates through which the metal is poured into the mold to cast the sleeper; the gates are indicated by the dotted lines G in the drawings, and the metal risers or heads formed in the gates at the time of casting the sleeper can be 100 readily broken off leaving the ribs 1^j in place.

The pairs of ribs 1^a, and 1^b, are arranged transversely of the plates of the sleeper, at about the longitudinal center thereof and approximately in line with the central rib 1^j, intermediate seats B and C. The spaces 105 110

2
between the ribs 1^d and 1^e form pockets E, F on the tie, and secured in such adjusted through which the nuts can be inserted into position. The sockets 1^s, hereinafter referred to. The outer ends of the ribs 1^e are preferably in- turned as at 1^k, or otherwise formed to engage the head of tie rods (not shown) such as are shown and described in my Patent No. 1,378,383, dated May 17, 1921; and by which the adjacent similar sleepers underlying opposite rails of the track can be securely bonded together.

In the top portion of the sleeper, adjacent the inner ends of the pairs of ribs 1^d and 1^e, are formed openings or sockets 1^s which are preferably angular in cross section and tapered or larger at the bottom than at the top. These sockets are adapted to receive angularly tapered nuts which can be inserted therein from beneath by entering the nuts between the ribs 1^d and 1^e as indicated in Figs. 1, 4, and 7.

After a rail R is mounted upon the wooden blocks W, the opposite sides of the rail are engaged by rail clamps 2 (see Figs. 4, 7, 8) which are polygonal, each being shown as four sided and having an eccentrically disposed opening 2^a for the passage of a securing bolt 3, and each clamp is provided in its sides with recesses 2^b adapted to receive the edge of the flange of the rail. The base portion 2^c of the clamp is provided with interconnected slots 2^e and 2^f at right angles to each other, and parallel with the sides. Either of these slots can be engaged with a link 5 which is provided with holes 5^a near its opposite ends adapted to register with the holes 2^a in the clamps. In applying the fastenings, after the rail is in place on the wooden seats (see Fig. 4) a link 5 is slipped under the rail transversely thereof, between the seats B and C and over the sockets 1^s. Then clamps 2 are slipped on the ends of the links until the holes 2^a in the clamps register with holes 5^a; then bolts 3 are passed through the clamps and plate and engaged with tapered nuts 4 which have been previously placed in the sockets 1^s. Then the bolts 3 may be tightened, by suitable wrenches, to bind the rail firmly to the sleeper.

In cases where it is desired to insulate the rail electrically, non-conducting bushings 6 may be placed between the nuts 4 and the walls of the sockets 1^s.

In order to compensate for wear, or variation in width of the rail bases the openings 2^a in the clamps are located eccentrically of the body of the clamp, as shown in Fig. 7; and by turning the clamp 90 degrees the actual distance between the edge of the rail and the center of the bolt can be varied and consequently different widths of rails can be secured, or wear on the rails can be compensated for as these adjustable clamps enable the rail to be adjusted slightly laterally

on the tie, and secured in such adjusted position.

The fastenings with the insulation shown enable the rails to be electrically insulated from the sleeper if the sleeper is to be used for electrical railways; or for portions of ordinary railways where electrical signaling is employed and the track rails form part of the electrical circuit. The rail fastening devices are very efficient, easily applied, and very strong; and also are easily adjustable to compensate for wear.

Preferably the nuts 4 are made of brass to prevent the nuts rusting to the sleeper, and to facilitate the removal or adjustment of the fastenings if it becomes necessary to remove or adjust rails.

The link ties the bolts on opposite sides of the rail together, so both contribute to prevent lateral displacement of the rail in either direction.

It is not necessary or desired to use concrete to fill the sleeper, as it may be filled with ordinary ballast. Any ballast that gets under the wings of the sleeper will work towards the center of the sleeper, and keep it tamped up.

The tie is preferably perforated with holes about $\frac{5}{8}$ inch in diameter. This enables the trackman to see that the sleeper is properly tamped up with broken stones; and the transverse integral strengthening ribs render the tie very rigid and prevent its yielding or breaking in case it should not be properly tamped.

I claim:

1. A sleeper adapted to extend lengthwise of the rail, comprising an approximately rectangular hollow body convex on its upper surface and concave on its under surface and having a longitudinal centrally disposed raised portion, and downwardly and outwardly inclined wings on opposite sides of said raised portion, whereby ballast is directed toward the center of the sleeper; the top of the central raised portion being provided with a plurality of rail seats substantially as described.

2. A sleeper as set forth in claim 1, having a tie engaging portion at one side, and openings or sockets for the engagement of rail fastening devices adjacent the rail seats.

3. A sleeper as set forth in claim 1, having transversely disposed depressions near its center, and sockets adjacent the inner ends of said depressions for the engagement of rail fastening devices, substantially as described.

4. A sleeper as set forth in claim 1, having angular tapered sockets adjacent opposite sides of the central raised portion thereof, and intermediate adjacent rail seats for the engagement of rail fastening devices.

5. A sleeper as set forth in claim 1, hav-

ing pairs of transversely disposed reinforcing ribs at opposite sides of the raised portion, sockets between the said pairs of ribs at opposite sides of the raised portion for 5 the engagement of rail fastening devices, and tie engaging members at the outer end of one of said pairs of ribs.

6. A sleeper adapted to extend lengthwise of the rail, said sleeper comprising an 10 approximately rectangular hollow body convex on its upper surface and concave on its under surface and having a longitudinal centrally disposed raised portion, and downwardly and outwardly inclined wings on 15 opposite sides of said raised portion, whereby ballast is directed toward the center of the sleeper; and having transversely disposed integral reinforcing ribs connecting the wings with the central portion, the top 20 of the central raised portion being provided with a plurality of rail seats substantially as described.

7. A sleeper as set forth in claim 6, having a tie engaging portion at one side, and 25 openings or sockets for the engagement of rail fastening devices adjacent the rail seats.

8. A sleeper as set forth in claim 6, having 30 transversely disposed depressions near its center, and sockets near the adjacent inner ends of said depressions for the engagement of rail fastening devices.

9. A sleeper as set forth in claim 6, having 35 angular tapered sockets adjacent opposite sides of the central raised portion thereof, and intermediate the adjacent rail seats for the engagement of rail fastening devices.

10. A sleeper as set forth in claim 6, having 40 pairs of transversely disposed reinforcing ribs at opposite sides of the raised portion, sockets between the said pairs of ribs and at opposite sides of the raised portion for the engagement of rail fastening devices, and tie engaging members at the 45 outer end of one of said pairs of ribs.

11. A sleeper adapted to extend lengthwise of the rail, and of greater length than width, comprising an approximately rectangular hollow body convex on its upper 50 surface and concave on its under surface and having a longitudinal centrally disposed raised portion, and downwardly and outwardly inclined wings on opposite sides of said raised portion; transversely disposed integral reinforcing ribs on the upper side of the said wings, connecting the same with the central portion; transversely disposed integral reinforcing ribs on its under side, and longitudinally disposed integral 55 reinforcing ribs on its underside; the top of the central raised portion being provided with a plurality of rail seats, substantially as described.

12. A sleeper as set forth in claim 11, 60 having a tie engaging portion at one side

and having openings or sockets for the engagement of rail fastening devices adjacent the rail seats.

13. A sleeper as set forth in claim 11, having transversely disposed depressions 70 near its center, and sockets near the adjacent inner ends of said depressions for the engagement of rail fastening devices.

14. A sleeper as set forth in claim 11, having angular tapered sockets adjacent opposite sides of the central raised portion thereof, and intermediate the adjacent rail seats for the engagement of rail fastening devices. 75

15. A sleeper as set forth in claim 11, having 80 pairs of transversely disposed reinforcing ribs at opposite sides of the raised portion, socket portions between the said pairs of ribs and at opposite sides of the raised portion for the engagement of rail fastening devices, and tie engaging members at the 85 outer end of one of said pairs of ribs.

16. A sleeper for the purpose specified 90 adapted to extend lengthwise of the rail, and of greater length than width, said sleeper comprising an approximately rectangular hollow body convex on its upper surface and concave on its under surface and having a longitudinal centrally disposed raised portion, downwardly and outwardly inclined wings on opposite sides of 95 said raised portion; transversely disposed integral reinforcing ribs on the upper side of the said wings, transversely disposed integral reinforcing ribs on its under side, and longitudinally disposed integral reinforcing ribs on its underside; the top of the 100 central raised portion being provided with a plurality of rail seats, the body of said sleeper having numerous perforations, said sleeper having a tie engaging portion at one side near the center, and having openings or sockets for the engagement of rail fastening devices. 105

17. In combination with a sleeper having rail seats, angular sockets at opposite sides 110 of said seats, clamps adapted to engage opposite sides of the flange of a rail, a link adapted to extend under the rail and engage said clamps, nuts in the sockets, and bolts transfixing the clamps and link and engaging the nuts.

18. In combination with a sleeper having rail seats, angular tapered sockets at opposite sides of said seats, clamps engaging opposite sides of the flange of a rail, a link 120 extending under the rail and engaging said clamps, angular tapered nuts in the sockets, and bolts transfixing the clamps and link and engaging the nuts.

19. In combination with a sleeper having rail seats, sockets at opposite sides of said seats, opposite clamps adapted to engage the opposite flanges of a rail having peripheral notches to engage the flanges and seats for engagement with a link, a link adapted to 125 130

extend under the rail and engage the slots in said clamps, nuts in the sockets, and bolts transfixing the clamps and link and engaging the nuts to secure the rail to the sleeper.

5 20. In combination with a sleeper having rail seats, angular tapered sockets at opposite sides of said seats, clamps adapted to engage opposite sides of the flange of a rail, and having transverse intersecting slots

for engagement with a link, a link adapted to extend under the rail and engage the slots in said clamps, angular tapered nuts in the sockets, and bolts transfixing the clamps and link and engaging the nuts to secure the rail to the sleeper.

15 In testimony that I claim the foregoing as my own, I affix my signature.

JOSEPH A. SILVER.
